UNITED STATES PATENT OFFICE.

WILLIAM C. ROURK, OF GOLDSBORO, NORTH CAROLINA.

DESIGN FOR A KEY-RING HOLDER.

48,610.

Specification for Design.

Patented Feb. 22, 1916.

Application filed July 3, 1914. Serial No. 848,964. Term of patent 7 years.

To all whom it may concern:

Be it known that I, WILLIAM C. ROURK, a citizen of the United States, residing at Goldsboro, in the county of Wayne, and State of North Carolina, have invented a new, original, and ornamental Design for a Key-Ring Holder, of which the following is a specification, reference being had to the accompanying drawing, forming part thereof.

Figure 1 is a perspective view of the key

ring holder, showing my new design. Fig. 2 is a rear elevation of the same. Fig. 3 is an edge elevation.

I claim:

The ornamental design for a key ring holder, as shown.

WILLIAM C. ROURK.
